UNITED STATES PATENT OFFICE.

JOHN J. RUTGERS, OF HOLLAND, AND BENJAMIN F. BRINKMAN, OF GRAND RAPIDS, MICHIGAN.

PNEUMATIC SHOE FORM OR LAST.

SPECIFICATION forming part of Letters Patent No. 601,306, dated March 29, 1898.

Application filed February 17, 1897. Serial No. 623,874. (No model.)

To all whom it may concern:

Be it known that we, JOHN J. RUTGERS, of Holland, and BENJAMIN F. BRINKMAN, of Grand Rapids, Michigan, citizens of the 5 United States, have invented certain new and useful Improvements in Pneumatic Shoe Forms or Lasts; and we do hereby declare the following to be a full, clear, and exact description of the invention, such as will enable 10 others skilled in the art to which it appertains to make and use the same.

Our invention relates to a pneumatic shoe form or last.

Our object is to provide a distensible inflatable last for stretching shoes, removing wrinkles from the leather, and various uses; and it consists in the construction, combination, and arrangement of the device herein described, pointed out in the claim, and illustrated in the drawings, in which—

Figure 1 represents a shoe distended by our device, which is shown in its proper position in use in dotted outline; Fig. 2, a side view of the device removed from the shoe, and Fig. 3 25 a vertical section of the same.

A represents the body, composed of a suitable air-tight semi-elastic fabric (preferably rubber) in the form of a shoemaker's last, the hollow interior corresponding in outline to the 30 exterior and having an insole B and an extra stiffened top portion C, provided with an air-valve D, communicating with said interior and having the end screw-threaded, as shown, for attaching to the nozzle of an air-pump for 35 inflating the last with air.

When used, the device is inserted into the shoe before inflation, then connected to the air-pump and inflated, thereby distending the

shoe. The valve prevents the return of the air. The pump is disconnected and the shoe 40 retains the form of the last until the valve is opened, permitting the air to escape, when the last collapses and is easily removed.

Shoes arranged for display in show-cases and windows are generally stuffed with batting, rags, paper, or similar material for distension. This process consumes time, requires skill to make the shoe have a symmetrical appearance, and is unsatisfactory. Our device is designed to furnish a substitute for 50 this process.

Our improved pneumatic last furnishes a means of quickly, permanently, and symmetrically distending and filling shoes used for the purpose of exhibition.

We claim—

As an improved article of manufacture, the herein-described pneumatic shoe form or last, comprising a body portion of air-tight semi-elastic fabric of the shape of a last or shoe corresponding when inflated to the interior of a shoe and collapsible when not inflated, an insole over which the fabric is stretched at its lower portion, a stiffened top portion over which the fabric is also stretched, and an air-valve secured in the stiffened top portion and passed through the fabric, all substantially as shown and described.

In testimony whereof we affix our signatures in presence of two witnesses.

JOHN J. RUTGERS.
BENJ. F. BRINKMAN.
